FOLDABLE BACKGUARD FOR ELECTRIC RANGES

Joseph Joy Woodburn, Cincinnati, Ohio, assignor to Avco Manufacturing Corporation, Cincinnati, Ohio, a corporation of Delaware

Application May 12, 1950, Serial No. 161,671

4 Claims. (Cl. 219—35)

1

The present invention relates to a backguard for attachment to a range and has more specific reference to a foldable backguard for use with an electric range wherein the control switches and similar electrical components are disposed within the backguard proper.

For a great many years it has been a common practice to pivot cover plates at the rear of ranges for covering the surface burners of the range when it was not in use, the covers being swung into a more or less vertical plane behind the range when the range was in use. Such pivoted cover plates have been made in many forms and have also been made to serve secondary purposes when the range was in use, such as, forming shelves and racks for supporting and drying objects at the rear of the range. Several of the prior art designs were constructed so that the cover plate, when swung into an upright position at the rear of the range, acted as a backguard or splash back.

According to my invention a foldable backguard is provided which is primarily intended to facilitate shipment and servicing of the unit. My invention is particularly useful when applied to an electric range in which the various electrical controls are disposed within the backguard proper.

In view of the foregoing, it is an object of the present invention to provide a foldable backguard for use with an electric range to facilitate the servicing of the electrical controls of the range not only by rendering more accessible its wiring and electric components but also by eliminating any need for moving the range away from any adjacent wall of the room in which it is used. Furthermore, use of the present invention makes it possible for persons servicing the range to work in a convenient upright standing position rather than behind the range in awkward, cramped quarters.

Another object of the invention is the provision of backguard supports which are rigidly assembled to the frame of the range but which are centrally pivoted to facilitate shipment without any necessity of removing the supports.

A very important object of the present invention is the provision of a foldable backguard which may be used in conjunction with a range having a substantially flat top.

A practical advantage of the present invention to manufacturers and distributors of electrical ranges is that the foldable backguard decreases the overall shipping height of the range compared to what it would be were the backguard

2

and its supports permanently assembled in an upright position to the range. The possibility of shipping ranges of a given size in smaller cartons and in smaller spaces will be recognized immediately as a very important advantage.

Another advantage that will have practical appeal to a housewife is that the present invention will permit washing or painting of wall surfaces behind and adjacent to the range without requiring that the range be moved away from the wall and without obstruction by any projecting supports at the rear of the range. This advantage will be of special importance in those homes where the range is placed in an alcove or recess.

15 The novel features that are considered characteristic of the invention are set forth in the appended claims; the invention itself, however, both to its organization and method of use together with additional objects and advantages 20 thereof will best be understood from the following description of a specific preferred embodiment, when read in conjunction with the accompanying drawings, in which:

25 Fig. 1 is a rear elevational view of the top portion of an electric range showing attached thereto a foldable backguard, having half of an associated wiring shield broken away to show the internal construction of the backguard;

30 Fig. 2 is an elevational cross-sectional view taken on plane 2—2 of Fig. 1, showing in section the backguard in its upright position assembled to the range;

35 Fig. 3 is an elevational cross-sectional view of the backguard and upper portion of the range showing the backguard and the upper portion of the wiring shield folded into a substantially horizontal position to facilitate servicing and shipment of the range; and

40 Fig. 4 is a horizontal sectional view taken on plane 4—4 of Fig. 1 showing the structural details of one of the expansion hinges to which the backguard is slideably attached.

General description

45 As shown particularly well in Fig. 2, the present invention is particularly well adapted for use in conjunction with an electric range, the main body portion of which is generally designated 1, having a backguard, generally designated 2, positioned adjacent the top rear edge thereof. As commonly provided, the electric range may have surface burners 3 which are regulated by control knobs 4 secured to shafts 5 of control switches 6 which are secured to and disposed 50 within the interior of the backguard. As shown

in Figs. 2 and 3, the backguard has a substantial depth to accommodate more readily these switches and related wiring 7 (see Fig. 1). When assembled, the range incorporates a wiring shield 8 which is essentially a piece of flat sheet iron secured to the rear face of the range to cover and protect the associated wiring.

In its assembled upright position, the backguard is firmly supported by and engaged with a pair of backguard supports, generally designated 9, each of which may include upper and lower portions joined by pivot pins 11. The backguard also cooperates with a pair of expansion hinges 10 which make possible movement of the backguard into a substantially horizontal position in conjunction with the upper portions of the supports.

Whenever it is necessary to ship the range or to service the electric controls, the backguard is detached from supports 9 and is moved from its upright assembled position shown in Fig. 2, to the position shown in Fig. 3. If the sole purpose for folding the backguard is to service the electric controls, upper portion 12 of the wiring shield need not be pivoted to its horizontal shipping position but instead may be left in the assembled upright position indicated in Fig. 2.

Structural details

The electric range of the present invention includes a range top panel 14 which incorporates a substantially flat cooking surface 15 supporting surface burners 3. The top panel is disposed adjacent side walls 16, the panel and walls being firmly secured to a frame, the top rear edge of which is indicated at 17. A pair of braces 17a may be provided between panel 14 and the frame to strengthen the assembled structure.

As indicated in Figs. 1 and 2 a long forwardly extending central recess 18 is defined at the rear of the top panel by a downwardly extending flange 18a formed integrally with the top panel above the top of the frame proper, indicated at 17.

Each backguard support consists of a main support body 19 which is secured, as by screws 20, to flanges 18a and the top rear edge of the frame proper. Pivotally secured to each support body 19 by a pivot pin 11 is a support extension 21, the extension comprising an elongated, channel shaped member having a tab 22 at its upper end which is perpendicular to the length of the extension.

When the backguard is supported at the rear of the range, a screw 23 secures each support extension 21 to its related support body 19 so that a rigid unitary support is created. The points of attachment of the supports, being spaced by a substantial distance, make possible rugged, firm installation with the main body portion of the range.

An expansion hinge member 24 is attached to flange 18a at each side of the range. As shown particularly well in Figs. 2 and 3 each hinge member is formed to define a vertically elongated slot 25 in which is slideably disposed a hinge pin, which may take the form of a shoulder bolt 26 secured by a nut 27 to a reinforcing gusset 28 provided at each lower corner of the backguard.

Sufficient clearance is provided between the shoulder bolts 26 and the slots 25 to permit free sliding action when the backguard is lifted off

of the upper ends of support extensions 21. Before the backguard can be lifted in this fashion, however, screws 29 at the top of the backguard must be removed from engagement with tabs 22 of the support extensions with which the screws are threadedly engaged. After these screws have been removed, the backguard with its electric controls may be lifted as an assembly until top flange 18b of the backguard clears the upper ends of the support extensions, after which the backguard may be subjected to a pure rotation being eventually moved into a substantially horizontal position as indicated in Fig. 3. A comparison of Figs. 2 and 3 will show that, during this movement of the backguard, shoulder bolts 26 remain engaged with the slots so that the backguard can not come loose from the range.

When the backguard is disposed in the position shown in Fig. 3, control switches 6 and their related wiring may be readily serviced. If necessary, the switches may be completely replaced. It is noteworthy that such extensive servicing is possible without any movement whatsoever of the range proper away from any wall surface that may be adjacent. The practical importance of this feature will be fully appreciated when it is remembered that modern electric ranges may weigh over 260 pounds when fully equipped. Furthermore, the accessibility of electric components made possible by the present invention avoids the need for any person's climbing between the range and the adjacent wall and working in cramped awkward quarters behind the range.

During shipment, the upper portion 12 of the wiring shield and the support extensions to which it is secured by screws 30, may be rotated as a unit about the axes of pivot pins 11 as indicated in Fig. 3. Before such a rotation is possible, however, screws 23 which secure the extensions 21 to the support bodies 19 must be removed. These screws, shown in full lines in Fig. 2 are threadedly engaged with the extensions 21 and lie above lower positions, indicated by phantom lines at 31, in which the screws are placed during shipment of the range. In the lower position (indicated by full lines in Fig. 3) the screws no longer engage the support extensions but merely are threadedly engaged in the support bodies alone thereby clamping the upper edge of the lower portion 13 of the wiring shield during shipment.

Notches 32 are provided at the upper corners of portion 12 of the wiring shield to permit engagement with reinforcing gussets 33 rigidly secured at the upper corners of the backguard. Additional slots 34 are provided in the lower edge of portion 12 to permit engagement of this portion of the wiring shield with the lower portion 13 as indicated in Fig. 1. Such engagement of portion 12 with the backguard proper and the lower portion of the wiring shield is readily accomplished when the backguard is placed in its assembled upright position by merely deflecting this portion of the wiring shield slightly until the slots embrace the associated edges of the gussets and lower portion of the wiring shield.

Use and assembly of the foldable backguard

When a range incorporating the present invention is shipped, the backguard and the upper portion of the wiring shield are disposed in a substantially horizontal position as indicated in Fig.

3. During shipment, protective pads of various sorts may be interposed between the backguard and the top surface of the range.

In order to assemble the range at its destination, screws 23 are removed from the position indicated at 31 and the support extensions, carrying the upper portion of the wiring shield, are rotated into the upright position. As the extensions approach this position, the upper portion of the wiring shield is deflected so that notches 34 engage the upper edge of the lower portion of the wiring shield. Thereafter screws 23 are shifted to their upper positions and are threadedly engaged with the support extensions to form a rigid support assembly.

The backguard assembly is then rotated and raised as a unit and is lifted over the top ends of the support extensions. The top edge of the upper portion of the wiring shield is disposed behind flange 18b of the backguard with notches 32 engaged with reinforcing gussets 33. The backguard is then lowered into the assembled position shown in Fig. 2 and screws 29 are threadedly engaged with tabs 22 to complete the assembly.

Should it be necessary to service the electric switches or wiring of the range, it is merely necessary to remove screws 29 and to fold the backguard forwardly as has been described hereinbefore. In the event that the range is again to be shipped, the screws 23 may be removed and shifted from their upper to their lower positions, thereby permitting the upper portion of the wiring shield and the associated support extensions to be rotated from the upright to the substantially horizontal position.

It will be obvious that the backguard and wiring shield may be folded to the horizontal position in a similar manner if it is necessary to clean any wall surface directly behind and adjacent to the range.

Having described a preferred embodiment of my invention, I claim:

1. In combination in an electric range having a frame structure above which is disposed a top panel, a foldable backguard positioned above the rear edge of said top panel, a plurality of expansion hinges joined to the top panel and said backguard whereby said backguard may be moved linearly and arcuately into a folded horizontal position above the top panel, a plurality of supports having hinged upper and lower portions, said lower portions being joined at their lower ends to the frame and the top panel, said upper portions extending vertically above the surface of the top panel for a distance substantially equal to the height of said backguard, means for releasably joining the upper and lower portions of said supports to render them rigid, and means for releasably securing said backguard to the upper portions of said supports when the upper portions of said supports are joined rigidly to said lower portions.

2. Apparatus as defined in claim 1 and in addition a wiring shield comprising upper and lower portions, the upper portion of said wiring shield being secured to the upper portions of said supports and movable therewith.

3. In combination in an electric range, a main body portion, a foldable backguard positioned adjacent the rear edge of said main body portion, a plurality of expansion hinges secured to said backguard and said main body portion to permit translatory and rotary movement of said backguard into a substantially horizontal folded position above said main body portion, a plurality of upright backguard supports comprising hingeedly connected upper and lower portions, said lower portions being rigidly secured to the rear face of said main body portion, the upper portions of said supports being positioned in supporting relationship with said backguard when in its vertical position, means for releasably securing said backguard to the upper portions of said supports, means for releasably joining each of said upper support portions to its related lower portion whereby said supports may be made rigid for supporting said backguard in its upright position, and a cover plate secured to the upper portions of said supports, the upper portions of said supports being movable as a unit with said cover plate to a substantially horizontal position above said backguard when in its folded position.
4. In combination in an electric range, a main body portion, a foldable backguard positioned adjacent the rear edge of said main body portion, means interconnecting said backguard and said main body portion to permit translatory and rotary movement of said backguard into a substantially horizontal folded position above said main body portion, a pair of rigid upright backguard supports each comprising an upper and a lower portion hingedly interconnected for pivotal movement about an axis intermediate the ends of said support, the lower portions of said supports being rigidly secured to the rear of said main body portion, the upper portions of said supports normally being positioned in supporting relationship with said backguard when in its vertical position, means for releasably securing said backguard to the upper portions of said supports, means for releasably joining each of said upper support portions to its related lower portion whereby said supports may be made rigid for supporting said backguard in its upright position, and a cover plate horizontally divided into two sections, the lower section being secured to the rear of said main body portion and the lower portions of said supports, the upper section of said cover being secured to the upper portions of said supports and being movable as a unit therewith to a substantially horizontal position above said backguard when in its folded position.

JOSEPH JOY WOODBURN.
